UNITED STATES PATENT OFFICE.

ERNEST JOSEPH WAGNER, OF PENSACOLA, FLORIDA.

INTERNAL-COMBUSTION ENGINE.

1,186,350.

Specification of Letters Patent. Patented June 6, 1916.

Application filed August 20, 1914. Serial No. 857,677.

To all whom it may concern:

Be it known that I, ERNEST J. WAGNER, a citizen of the United States, and a resident of Pensacola, in the county of Escambia and State of Florida, have invented a new and Improved Internal-Combustion Engine, of which the following is a full, clear, and exact description.

My invention relates to an internal combustion engine and which has for its object to provide means for scavenging the cylinder in an internal combustion engine at the termination of the power stroke and simultaneously opening the inlet port and 10 charging the cylinder with a combustible mixture. The desired result is obtained with an auxiliary piston which moves quickly when the main piston approaches the end of the power stroke to remove the 15 gases of combustion from between the main piston and the auxiliary piston, the new charge of combustible mixture being drawn in between the auxiliary piston and the cylinder head as the auxiliary piston moves 20 away from the said cylinder head. The combustible mixture is compressed as the auxiliary and main pistons are moved on their 25 return stroke. With the improvement much more horse power is obtained relatively to 30 the weight of the engine than is possible with the usual type four cycle engine, it being possible to operate any engine without mechanically operated valves.

Additional objects of the invention will 35 appear in the following specification in which the preferred form of my invention is disclosed.

In the drawings similar reference characters refer to similar parts in all the views 40 in which—

Figure 1 is a transverse sectional elevation of the engine; Fig. 2 is a side elevation in section showing the position of the pistons at the commencement of the power 45 stroke; and Fig. 3 is a sectional elevation similar to that shown in Fig. 2, but with the pistons in the positions which they assume at the end of the power stroke.

By referring to the drawings it will be 50 seen that the engine is provided with a cylinder 5 which may have a water jacket 6, the cylinder 5 having a head 7. In the cylinder 5 there is a main piston 8 and an auxiliary piston 9, the cylinder 5 being provided 55 with a by-pass 10 around the auxiliary piston 9 when the auxiliary piston 9 is in the

position which it assumes when the main piston is about to move on the power stroke. The ports 11 leading to the chamber 12 also serve as a by-pass around the auxiliary piston 9. An inlet port 13 communicates with this chamber 12, the inlet port 13 being normally closed by a valve 14 which is held yieldingly on its seat by the spring 15 in the customary manner. An igniter 16 also communicates with the interior of the chamber 12. Spaced from the cylinder head 7 the cylinder is provided with an exhaust 17.

As has been stated, the cylinder 5 not only has a main piston 8 but an auxiliary piston 9, the rods 18 being disposed through openings 19 in the auxiliary piston 9 and being held in place by the shoulders 20 which engage the underside of the auxiliary piston 9 and by the nuts 21 which mesh with the threaded terminals 22 of the rods 18 and which seat against the bottom of the recesses 23 in the auxiliary piston 9. The rods 18 extend down through openings 24 in the main piston 8 and have elongated 25 openings 25 in which are disposed the shaft sections 26, these shaft sections 26 having annular grooves 27 in which fit the rods 18 at the sides of the elongated openings 25. The shaft sections 26 are journaled 30 in bearings 28 in the frame 29, disks 30 being secured to the shaft sections 26, these disks 30 being spaced apart. A crank pin 32 extends across from one of the disks 30 to the other disk 30 and this crank pin 32 is journaled in the bearing 31 at the lower end of the piston rod 33, the bearing 31 having shoulders 34 which engage the inner sides of the disks 33 to hold the disks 30 spaced apart. The piston rod 33 is articulated within the bottom of the main piston 8 in the customary manner, the piston rod 33 having a bearing 36 in which is journaled a pin 35 secured to the main piston 8.

With the construction which has been described, the main piston 8 is adapted to rotate the shaft sections 26 in a manner readily understood. On the outer surfaces of the disks 30 there are cam grooves 37 in which are disposed for moving the rollers 38 on the studs 39 carried by the lower ends of the rods 18. As best shown in Figs. 2 and 3 one side 40 of each of the cam grooves is curved around the axis of the bearings 31, the other side 41 of the cam groove 37 being disposed at the other side of the axis of the bearing 31 and being substantially straight.

It will also be seen that one end of the cam groove 37 is disposed adjacent the axis of the shaft sections 26 while the other end of the cam groove 37 extends beyond the axis 5 of the bearing 31.

In the operation of the engine the combustible mixture is fed through the inlet port 13 when the auxiliary piston 9 moves downwardly at the end of the stroke of the 10 main piston 8, this downward movement of the auxiliary piston 9 serving to draw in the combustible mixture, the combustible mixture being compressed on the return stroke of the pistons 8 and 9. When the 15 pistons 8 and 9 reach the positions shown in Fig. 2 of the drawings, the charge is ignited, the pressure being substantially the same at each side of the auxiliary piston 9 because of the by-pass 10 and the passage 20 11 to the chamber 12. It will, therefore, be seen that the pressure will be exerted against the main piston 8 and that this main piston 8 will be forced downwardly to turn the shaft sections 26 by the means which has 25 been described. With the downward movement of the main piston 8 the rollers 38 will move into the straight portion 41 in the cam groove 37 and until the last part of the downward stroke of the main piston 8, the 30 rollers 38 will not be moved downwardly to draw down the auxiliary piston 9 by means of the rods 18, but as the main piston 8 is about to complete its stroke, the continued movement of the rods 38 in the straight portion 35 of the cam groove 37 will serve to draw down the auxiliary piston 9 quickly to force through the exhaust port 17, the products of combustion, a new charge being drawn into the upper portion of the piston 5 by the 40 suction which is caused as the auxiliary piston 9 moves downward. As the rollers 38 pass the straight portion 41 of the cam grooves 37 to the position shown in Fig. 3 of the drawings, the rollers 38 will then 45 move in the curved portion 40 of the cam grooves and in this way, the auxiliary piston 9 will be forced upward at substantially the same speed as the main piston 8, until the main piston 8 and the auxiliary piston 50 9 are disposed as shown in Fig. 2 of the drawings and with the combustible mixture compressed around both sides of the auxiliary piston 9 when the charge is again ignited in the manner described.

55 Having thus described my invention I

claim as new and desire to secure by Letters Patent:

1. In an internal combustion engine, a cylinder, a main piston for reciprocating in the cylinder, a pitman articulated to the 60 main piston, two shaft sections spaced apart, two disks, one secured to the end of each shaft section, a crank pin connecting the disks to which the pitman is articulated, there being two openings in the main piston separated by the connection of the pitman with the piston, an auxiliary piston in the cylinder, two rods connected with the auxiliary piston and one extending through each opening in the main piston, and cam 65 means at the outer sides of the disks for operating the rods.

2. In an internal combustion engine, a cylinder, a main piston for reciprocating in the cylinder, a pitman articulated to the 70 main piston, two shaft sections spaced apart, two disks, one secured to the end of each shaft section, a crank pin connecting the disks to which the pitman is articulated, there being two openings in the main piston, an auxiliary piston in the cylinder, two rods connected with the auxiliary piston and one extending through each opening in the main piston, the rods having slots through 75 which the shaft sections extend, and cam 80 means at the outer side of the disks for operating the rods.

3. In an internal combustion engine having a cylinder with a head, a main piston with an opening for reciprocating in the 85 cylinder, an auxiliary piston disposed between the main piston and the head, a shaft having an annular groove, a crank on the shaft, a piston rod connecting the main piston with the crank, there being a cam groove 90 in a member of the crank, a rod connected with the auxiliary piston, the last mentioned rod having an opening in which the shaft at the annular groove is disposed, the last mentioned rod extending through the 95 opening in the main piston and a cam member on the last mentioned rod for moving in the cam groove.

In testimony whereof, I have signed my name to this specification in the presence of 100 the two subscribing witnesses.

ERNEST JOSEPH WAGNER.
